PROCESS FOR THE MANUFACTURE OF MULTIPLE UNSATURATED ALIPHATIC COMPOUNDS

Hendrik Paul de Jongh and Filippus Johannes Zeelen,
Oss, Netherlands, assignors to Organon Inc., West
Orange, N.J., a corporation of New Jersey
No Drawing. Filed Oct. 3, 1966, Ser. No. 583,983
Claims priority, application Netherlands Oct. 18, 1965,
6513473

4 Claims. (Cl. 260—678)

ABSTRACT OF THE DISCLOSURE

Multiple unsaturated compounds of the formula

in which R is an alkyl group of 1 to 6 carbon atoms, are prepared by etherifying the hydroxyl group of a compound of the formula

in which R is an alkyl group of 1 to 6 carbon atoms, and treating the ether with an alkyl amide in liquid ammonia or a lower aliphatic amine. The products are intermediates for the synthesis of compounds of the vitamin A series.

The invention concerns a process for the manufacture of a multiple unsaturated aliphatic compound of the formula:

in which R represents an alkyl group with one to six carbon atoms, by conversion of a tertiary hydroxyl group of the starting material into an ether grouping, followed by splitting off said grouping while forming a double bond.

It has been known to convert alcohols of the type

in which R represents, for example, a lower alkyl group into an enyn by first preparing their tosylate, followed by their treatment with alkali, to obtain a double bond while splitting off of p-toluene sulphonic acid. On page 108 of Raphael's Handbook, "Acetylenic Compounds in Organic Synthesis," published in London by Butterworths Scientific Publications, 1959, this method is described. It is not well usable, however, if the starting product contains a tertiary hydroxyl group, because the tosylate of it is hard to obtain in a good yield.

Further it has been known from Berichte, 82, 276 (1949), first to convert the alcohol 1-ethoxy-3-hydroxy-3-methyl-hex-5-yne into the corresponding bromide, and to split off from it the hydrobromic acid with potassium hydroxide solution. It requires, however, reaction temperatures of 180–185° C., whereas yields are slight.

A process has been found now for the manufacture of multiple unsaturated, aliphatic compounds, by conversion of a hydroxyl group of them into a grouping that can be split off, while forming a double bond, followed by the introduction of the double bond, characterized in that a compound of the general formula

(I)

2

in which R represents an alkyl group whether or not branched with one to six carbon atoms, possibly substituted, is converted into an ether, treating it subsequently with an alkali metal amide in liquid ammonia, or a lower aliphatic amine. It is surprising that the ethers used as intermediate products can be converted in the alkali medium according to the invention, as it has been known that β -acetylene ethers are stable in alkaline medium, as goes forward, for instance, from the synthesis of 1-methoxy-but-3-yne from acetylene sodium and 1-methoxy-2-bromoethane in liquid ammonia, as described in J. Am. Chem. Soc., 59, 213 (1937). With the present method yields can be obtained of, for instance, 70%.

Further it has been found that, starting from the above compounds, in which R represents the group

in which R_1 represents an alkyl group with 1–6 carbon atoms, hence from 1,1-dialkoxy-3-hydroxy-3-methyl-hex-5-yne, after etherifying of the hydroxyl group, 2 ether groups can be split off while forming 2 double bonds to obtain the 1-alkoxy-3-methyl-hexa-1,3-dien-5-yne. The said starting products are known compounds, described in the U.S. patent specification 2,676,994 and used as intermediates for the synthesis of vitamin A.

The present final products are important intermediates for the synthesis of compounds of the vitamin A series. Thus by the coupling of 1-alkoxy-3-methyl-hexa-1,3-dien-5-yne with β -ionone compounds can be obtained directly of the carbon skeleton of vitamin A, as described in the published Netherlands patent application 6,404,175. These final products are also of importance for the synthesis of carotenes and carotenoids.

The ethers, functioning as intermediates in the method of preparation according to the invention, may be prepared in a conventional manner. Preferably they are prepared by the addition of the alcohol to a vinyl ether of the general formula:

in which R_3 , R_5 and R_6 represent hydrogen or an alkyl group with 1–6 carbon atoms and R_4 an alkyl group with 1–6 carbon atoms. Of these vinyl ethers especially those are applied of the formula: $\text{R}_4\text{O}-\text{CH}=\text{CH}_2$, in which R_4 represents an alkyl group with 1–4 carbon atoms, which ethers can be bought at a low price and give high yields. The splitting off of the ether group, while forming a double bond, is performed with an alkali metal amide, such as lithium, sodium and potassium amide, in liquid ammonia or a lower amine, such as methyl, ethyl and triethyl amine, which solvents may be diluted, if desired, with, for instance, benzene, toluene, dimethylformamide, dimethylacetamide and tetrahydrofuran. The amide may be added either to the ammonia or may be formed in it by dissolving the required amount of alkali metal in the presence of a small amount of ferrinitrate as catalyst.

The temperature at which the splitting off of the ether group occurs depends on the strength of the base used. When potassium amide is used, this reaction proceeds satisfactorily at a temperature of -30° C . to -65° C .

Further it has been found that the largest yields are obtained with the use of 5–15 mols of alkali metal amide per mol of ether. The metal compound formed in this reaction is decomposed with, for instance, ammonium chloride or a dilute mineral acid. The final product may be isolated from the reaction mixture by extraction with a solvent, for instance, ether. After drying the extract and removing the solvent the final product may be purified by fractionated distillation at reduced pressure.

According to the NMR-spectrum a mixture of chiefly

two stereo-isomers is formed in the preparation of hexadiyne, viz the cis-trans and the trans-trans isomer of the respective formulae:

The refraction indices observed of the mixture of isomers of 1-methoxy-hexadiyne are between 1.52 and 1.56, dependent on the ratio of cis-trans. By means of gaschromatography they may be separated, if desired. Both isomers can be used in the synthesis of vitamin A.

As examples of starting products of the present process are mentioned the compounds of the Formula I, in which R represents a methyl, ethyl, propyl, isopropyl and butyl group, which may be substituted by a hydroxyl group, an acyloxy group, an alkoxy group or by an amino group.

The ethers used as intermediates may be derived from, for instance, an aliphatic alcohol, such as methanol, ethanol, propanol and t-butanol from aromatic hydroxyl compounds, such as phenol, p-nitrophenol, p-chlorophenol and p-methoxyphenol, as well as from heterocyclic compounds, such as dihydropyran.

As examples of suitable vinyl ethers are mentioned: methoxy-ethene, ethoxyethene, butoxy and isobutoxyethene and further the compounds of the following formulae:

The preparation of the relative alkynyl ethers by means of these vinyl ethers takes place according to one of the common methods, for instance, by means of an acid, such as p-toluene sulphonic acid, dinitrobenzene sulphonic acid or anhydrous hydrochloric acid, or by means of a Lewis acid, such as borotrifluoride-etherate. The reaction may occur in a medium free from solvent or in an indifferent solvent, such as benzene, petroleumether, chloroform, carbontetrachloride, dialkylether, for instance, ethoxyethane, and in tetrahydrofuran or in a mixture of two or more of these solvents. The formation of the ether occurs at temperature between -30°C . and 100°C ., preferably at room temperature.

The alkynyl ethers formed in this reaction may contain one or two asymmetric carbon atoms, one of which may be present in the ether group to be split off. The reaction mixture obtained may therefore be a mixture of hardly separable diastereoisomers, which, as a mixture, are further converted.

Example 1

(A) To 61.13 gm. of 1,1-dimethoxy-3-hydroxy-3-methyl-hex-5-yne 68.78 gm. of ethyl-vinylether were added and, while stirring, 0.035 gm. of p-toluene sulphonic acid. The temperature rose in a short time to 53°C . and fell slowly afterwards. After 1 hour's stirring the reaction mixture was poured out into a saturated sodium chloride solution to which a small amount of potassium carbonate was added. The organic layer formed was separated from the water layer. The latter was extracted a few times with ether. The joint organic layers were next washed to neutral with a saturated sodium chloride solution. After drying on sodium sulphate, followed by filtration, the solvents were evaporated in vacuo. The residue was distilled in vacuo to obtain 60.75 gm. of crude 1,1-dimethoxy-3-(1-ethoxy-ethyl)-oxy-3-methyl-hex-5-yne. Boiling point $77-85^\circ\text{C}$. at 0.5 mm. Hg.

(B) With 48.08 gm. of potassium in 925 ml. of liquid ammonia and 0.62 gm. of $\text{Fe}(\text{NO}_3)_3 \cdot 9\text{H}_2\text{O}$ a solution

was made in the conventional manner of KNH_2 in liquid ammonia. At -40°C . 50 gm. of the ether obtained according to A were added to it in 45 minutes. After 1 hour's stirring 85 gm. of ammonium chloride were added, after which the ammonia was evaporated. Next 475 ml. of water were added, whereupon the mixture was extracted with hexane. The organic layers were filtered, washed with a saturated sodium chloride solution and dried on sodium sulphate. After filtration 0.25 gm. of α -tocopherol was added. The solvent was afterwards evaporated in vacuo, whereupon the residue was distilled in vacuo. Thus the 1-methoxy-3-methyl-hexa-1,3-dien-5-yne was obtained with a yield of 70% and a boiling point of $27-29^\circ\text{C}$. at 0.25 mm. Hg;

$\lambda_{\text{max}}^{\text{vis.}}: 21,500 \text{ at } 274 \text{ m}\mu$

Ratio cis-trans=7:5, calculated in the NMR spectrum.

Example 2

In the way of Example 1, starting from 1,1-diethoxy-3-hydroxy-3-methyl-hex-5-yne and dihydropyran, by means of a little p-toluene sulphonic acid as catalyst, the 3-tetrahydropyranylether was prepared. After isolation and distillation, it was converted at -50°C . into 1-ethoxy-3-methyl-hexa-1,3-dien-5-yne with sodium amide in liquid ammonia, in which process 10 mol of sodium amide per mol of ether were used. After addition of ammonium chloride and water to this reaction mixture, the organic layer formed was extracted with hexane and the extract filtered, washed and dried on Na_2SO_4 . Finally the hexadiyne, after removal of the hexane and distillation, was obtained in a yield of 60% relating to the starting product.

Example 3

(A) In 800 ml. of liquid ammonia the sodium amide was made from 0.1 mol of sodium and a trace of ferric nitrate. After cooling to -75°C . to 0.1 mol of 3-hydroxy-3-methyl-hex-5-yne, boiling point 48°C . at 13 mm. Hg, dissolved in 60 ml. of tetrahydrofuran was added to it. Next were added 6.5 ml. of methyliodide. After 3 hours' stirring at -75°C . the ammonia was evaporated and water was added gently. The water layer was next extracted with ether. The organic layers obtained were washed till neutral reaction. After drying on sodium sulphate the extract was filtered and the solvent evaporated in vacuo. Finally the residue was distilled in vacuo to obtain crude 3-methoxy-3-methyl-hex-5-yne.

(B) In the conventional manner, from 123 gm. of sodium in 3 l. of liquid ammonia, the sodium amide was prepared by means of a little ferric nitrate. To the grey suspension obtained were added at -40°C . 50 gm. of 3-methoxy-3-methyl-hex-5-yne in 30 minutes at -40°C . After 4 hours' stirring 300 gm. of solid ammonium chloride were added gently. Next the ammonia was evaporated while water was added gently. After extraction with hexane the organic layers were filtered, washed with a saturated sodium chloride solution and dried on sodium sulphate. Next the extract was filtered and 0.25 gm. of α -tocopherol was added. The solvent was evaporated in vacuo, whereupon the residue was distilled in vacuo. Thus the 3-methyl-hex-3-en-5-yne was obtained in a yield of 54%.

Example 4

In an analogous manner as described in Example 3 from 5-hydroxy-5-methyl-oct-7-yn the 5-pyranylether was prepared and after isolation with KNH_2 in liquid ammonia converted into the 5-methyl-octa-5-en-7-yne in a yield of 56%.

What is claimed is:

1. Process for the manufacture of unsaturated compounds of the formula:

in which, R represents an alkyl group having 1-6 carbon atoms, which may be branched and substituted, comprising etherifying the hydroxyl group of a compound of the formula:

in which R has the above meaning, and treating said ether with an alkali metal amide in a liquid selected from the group consisting of liquid ammonia and a lower aliphatic amine.

2. The process of claim 1 in which a compound of the formula:

in which R_1 represents an alkyl group with 1-6 carbon atoms, is used as starting material from which, after

etherifying the hydroxyl group, two ether groups are split off while forming the compound of the formula:

5 3. The process of claim 1 in which the starting product is etherified by addition to a vinyl ether of the formula:

10 10 in which R_3 , R_4 and R_6 represent a member of the group consisting of hydrogen and an alkyl group with 1-6 carbon atoms and R_4 an alkyl group with 1-6 carbon atoms.

15 4. The process of claim 1 in which per mol of ether 5 to 15 mol of alkali metal amide are used.
